Paul H. Wolff, INVENTOR

BY
Paul H. Wentworth
his ATTORNEY.

UNITED STATES PATENT OFFICE.

AARON H. WOLFF, OF NEW YORK, N. Y.

GAS HEATER.

Application filed July 26, 1923. Serial No. 653,884.

My invention relates to gas heaters, and more particularly to a heater of the type in which refractory elements are made incandescent by the direction of a Bunsen burner flame

5 against same.

In heaters of this type, the heat of the flame is intense, and it is necessary to provide an effective insulation between the refractory elements or radiants and the metal portion of 10 the heater, the usual practice being to form a combustion chamber about the radiants by means of a suitably formed fire brick.

Heaters of this type are well known in the art, my invention relating more particularly 15 to those structural characteristics by which any unconsumed gas, and products of combustion, may be conveyed from adjacent the combustion chamber so as to prevent any possibility of the escape of such gases to within 20 a room. This construction at the same time permits the heater to be positioned within a room having no fireplace, and be connected with a flue for conducting such gases directly from the combustion chamber to a flue. I 25 am thus enabled to dispense with the usual and well known type of hood overhanging the combustion chamber at the front of the heater, which hood has the two-fold disadvantage of interfering with the field of vision 30 from above the heater and involving an unsightly adjunct to the heater which precludes the employment of artistic designs in the heater casing.

In a heater embodying my invention, I secure a strong draft adjacent the top of the radiants, which will effectively remove all 35 gases from within the combustion chamber without in any way interfering with the effective application of the flames from the 40 burners to the radiants for bringing them to incandescence. The construction is also such that an effective cooling circulation is maintained between the back wall of the combustion chamber and the back of the heater casing 45 so as to avoid likelihood of radiant heat from the wall of the combustion chamber igniting any object against which the heater may be set. This cooling circulation also tends to assist in maintaining an effective suction or 50 draft for withdrawing the gases from within the combustion chamber and in preventing overheating of the smoke pipe connecting the heater with a flue in the building in which it is used.

55 The heater of my invention contemplates the employment of radiants so constructed as

to avoid the forward deflection of the products of combustion, or of unconsumed gases, toward the front of the combustion chamber and permit these gases to freely flow upwardly from within the radiants to the passages leading to the flue chamber rearwardly of the back wall of the combustion chamber.

The invention consists primarily in a gas heater embodying therein a casing having an opening in the front wall thereof, combustion chamber forming means having a forwardly directed top and a back wall rearwardly of said opening, a plurality of burners, opening into the bottom of said combustion chamber, 70 a radiant element above each of said burners and extending adjacent the top of said combustion chamber, and a back plate for said casing spaced sufficiently away from the back wall of said combustion chamber forming 75 means to form a flue chamber rearwardly of said combustion chamber, said back plate having an opening through the back wall thereof adapted to receive a flue pipe, and said combustion chamber forming means 80 having an opening therethrough adjacent the top of each radiant element whereby gases will flow from said combustion chamber, and through said flue chamber and the opening therein; and in such other novel features of 85 construction and combination of parts as are hereinafter set forth and described, and more particularly pointed out in the claims hereto appended.

Referring to the drawings,

Fig. 1 is a front perspective view of a heater embodying my invention;

Fig. 2 is a section on the line 2—2 of Fig. 1; and

Fig. 3 is a detail view from the back of one 95 of the radiant elements.

Like letters refer to like parts throughout the several views.

In the embodiment of my invention shown in the accompanying drawings, *a* indicates 100 the main casing of the heater which has a front opening therein indicated at *b*. Extending forwardly of the lower part of this opening is a corrugated burnished plate *c* for reflecting light rays from the radiant or 105 refractory elements.

Rearwardly of the plate *c* is a partition *d* forming a support for a sequence of burners *e* of a construction heretofore employed by me in heaters of the general type to which 110 this invention relates, the construction of which burners being old and well known in

the art, requires no detailed description beyond that it is of a type producing a long blue flame, being of the general type of Bunsen burners, but a special embodiment thereof.

Extending substantially parallel with the partition *d* for a short distance rearwardly of the top of the opening *b*, is a substantially horizontal plate *a'*, the function of which is to form part of the top of the heater casing *a* and assist in maintaining in position the fire brick forming the combustion chamber.

The top of the casing *a*, rearwardly of the plate *a'*, projects upwardly in a generally inclined position as indicated at *a''*, this portion *a''* serving somewhat as a deflector plate in directing gases toward an exhaust opening, in a manner which will be more fully referred to hereinafter.

The combustion chamber is formed of a fire brick *f* having forwardly directed side wings *f'* and an overhanging forwardly directed top *f''*. The fire brick *f* rests upon the top of the partition *d* with the back wall thereof rearwardly of the burners *e*, the side walls thereof engaging the edges about the opening *b* and the top thereof engaging the plate *a'*, a construction which will prevent accidental toppling of this brick rearwardly of the casing, since its four edges are closely confined by different portions of the heater casing. To prevent the brick being forced rearwardly of the casing, I provide a flange or bracket *g* secured to the partition *d*, and if desired a top flange or bracket *g'* secured to the plate *a'* may also be employed, although this is non-essential, since the engagement of the top of the brick with the plate *a'* will prevent any movement of the top of the brick inwardly of the casing.

40 The refractory elements or radiants shown at *h* rest upon the partition *d* within the side wings *f'* and overhanging top *f''*, these radiants having a vertically extending central passage therein, with suitable openings 45 to permit air to enter the space within the radiants, and at the same time form strips of small bulk so that the gas flame may readily bring same to the desired state of incandescence. The general construction of these radiants is old and well known in this art, the construction, however, being modified to provide an upwardly presented opening *h'* adjacent the top of the radiants, and an opening *h''* extending therethrough and 50 communicating with an opening *i* extending through the back wall of the fire brick *f* and adjacent the top thereof. By this construction any unconsumed gases and the products of combustion, flowing upwardly through 55 and about the radiants, will pass through the opening *i* to the rear of the fire brick into a flue chamber formed rearwardly of said brick by means of the back plate *a''* of the heater casing.

60 The plate *a''* has an opening therethrough

adjacent and above the opening *i* in the brick *f*, and the deflecting top *a''* of the casing *a*, and has a nipple *a''* extending rearwardly of the plate *a''* to facilitate the attachment of a stove pipe with the heater.

70 The back plate *a''* is spaced rearwardly of the fire brick *f* for a sufficient distance to afford a flue chamber of the desired capacity, and to at the same time position this plate a sufficient distance from the wall of the fire brick to minimize likelihood of overheating this plate to an extent which might result in the ignition of any article with which the plate may come in contact.

75 As a still further preventive of likelihood of starting a fire as a result of overheating of the back plate, I provide the partition *d* with a plurality of openings *d'* to permit air to flow from below the said partition upwardly 80 through the flue chamber between the back wall of the fire brick *f* and the back plate *a''*, to its outlet opening within the nipple *a''*.

85 The side wings *f'* of the fire brick *f* extend forwardly to a sufficient extent to bring each radiant in its entirety within the combustion chamber, and to effectively prevent the escape of gases forwardly of the combustion chamber. The radiants *h* are of a length substantially equalling the height of the combustion chamber.

90 The operation of the herein described heater is substantially as follows:—

95 When assembling the heater, the fire brick *f* is inserted through the opening *b* until the back thereof engages the flanges or brackets *g*, and the brackets *g'* when such are used, the overhanging top *f''* having a fairly close fit with the plate *a'* and the bottom of the back, and the side wings *f'* of the brick resting firmly upon the partition *d*.

100 The opening *i* is preferably formed close to the overhanging top *f''* so that gases rising against this top will be deflected through this opening into the flue chamber between the fire brick *f* and the back plate *a''*.

105 Since when the opening *a''* at the nipple is connected with a flue, there will be a natural draft, a constant circulation of air will be maintained through the flue chamber both 110 through the openings *d'* in the partition *d* and above the various radiants *h* through the opening *i* in the fire brick *f*.

115 When the various burners *e* are lighted, the products of combustion and any unconsumed gases will be drawn through the opening *i* particularly in the absence of a closed top to the radiant and the presence of upwardly and rearwardly presented openings *h'* and *h''* at the top thereof. As stated above, the overhanging top *f''* will also serve to deflect any of the rising heated gases toward the opening *i* so as to prevent the escape of any of such gases through the open front of the combustion chamber to within a room.

120 The capacity of the opening at the nipple

a^4 is proportioned to that of the various openings i and openings d' so as to secure an effective draft.

The inclined top plate a^2 and the position-
5 ing of the opening at the nipple a^4 above the openings i , either in part or in its entirety, will require upward flow of the heated gases when passing from the openings i to the opening at the nipple a^4 .

10 The admixture of cool air drawn through the openings d' and the heated gases passing through the openings i will have the effect of preventing overheating of the portions of the top of the casing a rearwardly of the fire 15 brick f and the continual flow of this cool air will serve to effectively prevent heat radiated from the back of the fire brick f , bringing the back plate a^3 of the heater casing to a temperature sufficiently high to introduce any fire 20 hazard from this source, in the use of the heater. The overhanging top f^2 and side wings f' of the fire brick will protect the side walls of the casing about said fire brick to prevent overheating at such points and also 25 of the top plate a' . The use of the overhanging top f^2 is primarily for the purpose merely of protecting, and preventing the destruction of the finish of, the top plate a' , and it is apparent that other means of effecting this result may be employed, if so desired, although the employment of this means in the fire brick is an economical and effective way of accomplishing the desired result.

30 The heater of my invention is designed for use in localities where it is required, by reason of the quality of the gas supply, to provide a flue connection to carry off injurious fumes resulting largely from incomplete combustion of the gases.

40 It will be noted that with the construction herein described, the arrangement is such as to effectively conduct such gases from within the combustion chamber at a point which will not interfere with the action of the flame upon the material of the radiants, and in fact in a manner which will increase the effectiveness of this flame as a result of the presence of a draft across the top of the radiants, since this draft will tend to elongate the flame and increase the range of contact with the different small strips of said radiants.

45 It is not my intention to limit the invention to the precise details of construction shown in the accompanying drawings. It is apparent that while I have shown a sequence of openings i through the fire brick, this arrangement is largely a matter of convenience and for securing the desired additional strength at this point of the fire brick. It has the advantage, however, of concentrating the draft above each radiant, although if it is desired to sacrifice this advantage, the arrangement shown need not be followed.

50 The manner of mounting the radiants in the combustion chamber upon the partition d is

old and well known in this art, and forms no part of my present invention.

Having described the invention, what I claim as new and desire to have protected by Letters Patent, is:—

70 1. A gas heater embodying therein a casing having an opening in the front thereof, combustion chamber forming means having a forwardly directed top, and a back wall rearwardly of said opening, a plurality of burners, opening into the bottom of said combustion chamber, a radiant element above each of said burners and extending adjacent the top of said combustion chamber, and a back plate for said casing spaced sufficiently so away from the back wall of said combustion chamber forming means to form a flue chamber rearwardly of said combustion chamber, said back plate having an opening therethrough adapted to receive a flue pipe, and said combustion chamber forming means having an opening through the back wall thereof adjacent the top of each radiant element whereby gases will flow from said combustion chamber, and through said flue chamber and the opening therein.

75 2. A gas heater embodying therein a casing having an opening in the front thereof and a plate above said opening, a fire brick within said opening having side wings, a back wall and a forwardly directed top below said plate said back wall having openings therethrough adjacent the top thereof, whereby a combustion chamber is formed rearwardly of said opening, a plurality of burners, opening into

80 the bottom of said combustion chamber, a radiant element above each of said burners and extending adjacent the top of said combustion chamber and an opening through the back wall of said fire brick, and a back plate for

85 said casing spaced sufficiently away from the rear wall of said fire brick to form a flue chamber rearwardly of said combustion chamber, said back plate having an opening therethrough adapted to receive a flue pipe, whereby gases will flow from said combustion chamber, and through said flue chamber and the opening therein.

90 3. A gas heater embodying therein a casing having an opening in the front thereof and a plate above said opening, a partition supported by said casing below and rearwardly of said opening, a fire brick within said opening and between said plate and said partition, said fire brick having side wings, a back wall and a forwardly directed top, said back wall having openings through the back wall adjacent the top thereof, whereby a combustion chamber is formed rearwardly of said opening, a plurality of burners, opening into the bottom of said combustion chamber, a radiant element above each of said

95 burners and extending adjacent the top of said combustion chamber and an opening through the back wall of said fire brick, and

a back plate for said casing spaced sufficiently away from the rear wall of said fire brick to form a flue chamber rearwardly of said combustion chamber, said back plate having an opening therethrough adapted to receive a flue pipe, whereby gases will flow from said combustion chamber, and through said flue chamber and the opening therein.

4. A gas heater embodying therein a casing having an opening in the front thereof and a plate above said opening, a fire brick having side wings and an overhanging top within said opening and below said plate and having openings through the back wall adjacent the overhanging top thereof, whereby a combustion chamber is formed rearwardly of said opening, a plurality of burners, opening into the bottom of said combustion chamber, a radiant element above each of said burners and extending adjacent the top of said combustion chamber and adjacent an opening through said back wall, and a back plate for said casing spaced sufficiently away from the rear wall of said fire brick to form a flue chamber rearwardly of said combustion chamber, said back plate having an opening therethrough adapted to receive a flue pipe, whereby gases will flow from said combustion chamber, and through said flue chamber and the opening therein, said flue opening having a capacity equaling the aggregate capacities of the openings through said back wall.

5. A gas heater embodying therein a casing having an opening in the front thereof and a plate above said opening, a partition supported by said casing below and rearwardly of said opening, a fire brick within said opening and between said plate and said partition, said fire brick having side wings, a forwardly directed top, and a rear wall having openings therethrough adjacent the top thereof, whereby a combustion chamber is formed rearwardly of said opening, a plurality of burners opening into the bottom of said combustion chamber, a radiant element above each of said burners and extending adjacent the top of said combustion chamber adjacent an opening through the rear wall of said fire brick, and a back plate for said casing spaced sufficiently away from the rear wall of said fire brick to form a flue chamber rearwardly of said combustion chamber, said back plate having an opening therethrough adapted to receive a flue pipe, whereby gases will flow from said combustion chamber, and through said flue chamber and the opening therein, said partition having an opening therethrough communicating with said flue chamber, whereby a cooling circulation of air is maintained between the rear wall of said fire brick and said back plate.

6. A gas heater embodying therein a casing having an opening in the front thereof, a plate above said opening and an upwardly and rearwardly inclined deflector plate, a

fire brick within said opening and below said plate, having side wings, a forwardly directed top, and a rear wall having openings therethrough adjacent the top thereof and below said deflector plate, whereby a combustion chamber is formed rearwardly of said opening, a plurality of burners, opening into the bottom of said combustion chamber, a radiant element above each of said openings and extending adjacent the top of said combustion chamber and adjacent an opening through the rear wall of said fire brick, and a back plate for said casing spaced sufficiently away from the rear wall of said fire brick to form a flue chamber rearwardly of said combustion chamber and said deflector plate, said back plate having an opening therethrough adapted to receive a flue pipe positioned adjacent said deflector plate and above the openings through the back wall of said fire brick, whereby gases will flow from said combustion chamber and through said flue chamber and the opening therein.

7. A gas heater embodying therein a casing having an opening in the front thereof, a plate above said opening and an upwardly and rearwardly inclined deflector plate, a partition supported by said casing below and rearwardly of said opening, a fire brick having side wings, a rear wall, and an overhanging top within said opening and between said plate and said partition, whereby a combustion chamber is formed rearwardly of said opening, a plurality of burners, opening into the bottom of said combustion chamber, a radiant element having an open top and an opening through the back wall adjacent the top thereof, positioned above each of said burners and extending adjacent the top of said combustion chamber, the rear wall of said fire brick having openings therethrough adjacent said overhanging top, one of said openings being positioned above each of said radiant elements, and a back plate for said casing spaced sufficiently away from the rear wall of said fire brick to form a flue chamber rearwardly of said combustion chamber and said deflector plate, and said back plate having an opening therethrough adapted to receive a flue pipe positioned adjacent said deflector plate and above the openings through the rear wall of said fire brick, whereby gases will flow from said combustion chamber and through said flue chamber and the opening therein.

8. A gas heater embodying therein a casing having an opening in the front thereof, a plate above said opening and an upwardly and rearwardly inclined deflector plate, a partition supported by said casing below and rearwardly of said opening, a fire brick having side wings, a rear wall, and an overhanging top within said opening and between said plate and said partition, whereby a combustion chamber is formed rearwardly of said

opening, a plurality of burners, opening into the bottom of said combustion chamber, a radiant element having an open top and an opening through the back wall adjacent the top thereof, positioned above each of said burners and extending adjacent the top of said combustion chamber, the rear wall of said fire brick having openings therethrough adjacent said overhanging top, one of said openings being positioned above each of said radiant elements, and a back plate for said casing spaced sufficiently away from the rear wall of said fire brick to form a flue chamber rearwardly of said combustion chamber and said deflector plate, and said back plate having an opening therethrough adapted to receive a flue pipe positioned adjacent said deflector plate and above the openings through the rear wall of said fire brick, whereby gases will

flow from said combustion chamber, and 20 through said flue chamber and the opening therein, and said partition having an opening therethrough communicating with said flue chamber, whereby a cooling circulation of air is maintained between the rear wall of 25 said fire brick and said back plate.

9. In a gas heater, a combustion chamber forming fire brick including therein forwardly extending side wings, a rear wall, and a forwardly overhanging top, and having a 30 series of small openings adapted to register with openings through the back wall of radiant elements used in conjunction with said fire brick through the rear wall thereof below said overhanging top. 35

In witness whereof I have hereunto affixed my signature, this 19th day of July, 1923.

AARON H. WOLFF.
